UNITED STATES PATENT OFFICE

2,171,856

VACUUM CLEANER

Gustaf Einar Lofgren, Riverside, Conn., assignor
to Electrolux Corporation, Dover, Del., a corporation of Delaware

Application April 27, 1938, Serial No. 204,499

4 Claims. (CL 183—51)

My invention relates to vacuum cleaners and more particularly to vacuum cleaners of the inside bag type.

In vacuum cleaners of the, so-called, inside bag type the dust separating member or dust bag is located within the casing of the vacuum cleaner unit. The cleaner unit is normally supported on a horizontal axis and the dust bag is located in one end of the unit. A removable end cover permits the removal and replacement of the dust bag. When the dust bag, which is being removed, is substantially full considerable difficulty may be experienced in removing the dust bag without spilling some of the dirt near the mouth of the bag.

In accordance with my invention a dust bag receiving opening is arranged to reduce to a minimum the likelihood of spilling dirt from the dust bag while it is being removed from the vacuum cleaner unit.

My invention also contemplates the provision of a separate member secured to the casing of the vacuum cleaner unit forming the dust bag opening with means for securing the dust bag in the casing and permitting its ready removal.

What I consider to be novel and my invention may be better understood by reference to the following specification and appended claims when considered in connection with the accompanying drawings, in which

Fig. 1 is a side view of a vacuum cleaner broken away in part;

Fig. 2 is an end view on an enlarged scale of the front end ring of the vacuum cleaner unit;

Fig. 3 is a side sectional view of the front end of the vacuum cleaner unit with the front end cover removed;

Fig. 4 is an enlarged sectional detail view taken along the line 4—4 of Fig. 2;

Fig. 5 is a sectional view similar to Fig. 3 except with the front end cover secured to the vacuum cleaner unit casing;

Fig. 6 is a side view of the front end of the vacuum cleaner unit showing the dust bag partially removed; and

Fig. 7 is a perspective view of the front end of the vacuum cleaner unit with the front cover removed.

Referring to the drawings, the numeral 10 indicates generally a vacuum cleaner unit of the inside bag type with a casing 11 supported on a horizontal surface 12 by means of sleighs 13. Vacuum cleaner unit 10 is connected to a cleaning tool 14 by means of a flexible hose 15 and a substantially rigid tubular member 16. A dust

separating member or dust bag 17 is located in the casing 11 at the front end, shown at the left in Fig. 1. Dust bag 17 is secured in casing 11 by means of a removable front end cover 18. Flexible hose 15 is connected in an inlet opening 19 provided in front end cover 18. A multi-stage centrifugal fan 20 driven by an electric motor 21 is mounted in casing 11 and produces a flow of air from front to rear of casing 11 or from left to right as shown in Fig. 1. When flexible hose 15 is connected to inlet opening 19 the flow of air produced by the operation of fan 20 results in a suction or partial vacuum at the cleaning tool 14. When the cleaning tool 14 is resting on a rug or other surface, air drawn in by the suction will carry with it dirt located on the rug or other surface. The dirt-laden air will travel in the direction indicated by the arrows in Fig. 1. As the air passes through the dust bag 17 any dirt carried by it will be separated from it. The air then passes through the fan 20, through or around the motor 21, and out of the casing 11 through an exhaust opening 22.

Dust bag 17 may be removed from or replaced in casing 11 through an opening formed in a ring 23 secured around the open front end of casing 11. As may be seen by reference to Figs. 2 and 3, ring 23 is formed with an inwardly extending flange 24 spaced from the adjacent front surface 25. A metal ring 26 is secured to dust bag 17 and is provided with an outwardly extending flange 27 that overlies the flange 24 of ring 23. An annular gasket 28 of rubber or other flexible material with a U-shaped cross-section is secured to the flange 27 of dust bag ring 26. Gasket 28 rests upon flange 24 of ring 23. An annular recess 29 of ring 23 receives the end of casing 11. Ring 23 may be secured to casing 11 by means of a plurality of bolts. One such bolt 30 is shown in Fig. 3 passing through an opening in a bracket 31 secured to casing 11 and entering a threaded aperture in ring 23. As may be seen upon reference to Figs. 2 and 4, two tapered cavities 32 are provided in ring 23 extending from the flange 24 to the front surface 25. Extending forwardly from the front surface 25 are two bosses 33. Bosses 33 enter openings in front end cover 18 and are engaged by locking mechanism, not shown, for securing the cover to the casing 11 and for holding dust bag 17 in casing 11. When cover 18 is secured to casing 11 a plate 34, see Fig. 5, compresses gasket 28 against flange 24. In this manner dust bag 17 is securely held in casing 11 and an air-tight seal

45

50

55

for the dust bag opening is produced by gasket 28.

In the use of the vacuum cleaner unit 10 for cleaning purposes dirt collects in the dust bag 17. The air passes approximately equally through all parts of the dust bag 17 and so the dirt separated from the air collects about equally on all parts of the dust bag. As a result, there is about the same amount of dirt accumulated around the sides of dust bag 17 at its mouth as along the sides in the interior of the dust bag. When it is desired to empty the dirt collected in the dust bag 17 the front end cover 18 is removed. The removal of the front cover 18 does not cause the dirt in the mouth of the dust bag 17 to fall on the rug or floor on which the vacuum cleaner unit 10 is located because the ring 23 is mounted at an angle to the vertical and the dust bag ring 26 rests in an inclined position with the mouth of dust bag 17 opening upwardly. However, unless care is exercised some dirt may be spilled from the dust bag as it is removed from casing 11. The danger of spilling dirt in removing the dust bag is obviated if the dust bag ring 26 is grasped at the bottom by fingers inserted in cavities 32 and the ring 26 raised by pivoting it on the top edge against the shoulder between the flange 24 and top surface 25. An intermediate position of dust bag 17 as it is being removed from casing 11 is shown in Fig. 6. After the mouth of dust bag 17 is inclined upwardly at a sufficiently great angle the dust bag may be removed bodily from casing 11. The dust bag 17 may then be carried to a receptacle and emptied in the usual manner.

In some cases it is found desirable to empty the dust bag on a paper or other receptacle placed adjacent the cleaner unit. This may be done by placing the paper under the front end of the vacuum cleaner unit 10. After the front end cover 18 has been removed the dust bag ring 26 may be grasped at the top where the depth of the flange 24, below the top surface 25 is less than at the bottom, as may be seen in Fig. 3. The dust bag ring 26 may then be pivoted quickly downward with its bottom edge engaging the shoulder between the flange 24 and top surface 25. This last movement has to be performed quickly because as soon as the mouth of the dust bag is inclined downwardly the dirt located around its mouth will begin to fall out and may cover a larger area than desired. The dirt may then be emptied on the paper.

What I claim is:

1. A vacuum cleaner comprising a casing having an opening, a ring secured to said casing around said opening, an inwardly extending

flange of said ring spaced from the forward surface of the ring and forming a dust bag seat, a dust bag, and a dust bag ring resting on said flange, said first-named ring having bottom cavities whereby said dust bag ring may be grasped and pivoted upwardly against the shoulder between said flange and the forward surface of the ring for removing the dust bag without disturbing the dust collected around the mouth of the bag.

2. A vacuum cleaner including a casing having an opening, a ring secured to said casing around said opening and inclined to a vertical plane, a flange extending inwardly from said ring forming a dust bag seat spaced from the front surface of the ring, and a dust bag having a ring resting on said flange, said first-named ring having a tapered cavity in the front surface extending to said flange whereby said dust bag ring may be grasped at the bottom and pivoted upwardly against the shoulder at the top of the ring between the front surface and the flange for removing the dust bag from the casing without disturbing the dust collected within the bag.

3. A vacuum cleaner including a casing having an opening, a ring secured to said casing around said opening and inclined to a vertical plane, a flange extending inwardly from said ring forming a dust bag seat spaced from the front surface of the ring, and a dust bag located within said casing having a ring resting on said flange with the mouth of the dust bag opening upwardly, said first-named ring having tapered cavities in the front surface extending to said flange whereby said dust bag ring may be grasped at the bottom and pivoted upwardly against the shoulder at the top of the ring between the front surface and the flange for removing the dust bag from the casing without disturbing the dust collected within the bag.

4. A vacuum cleaner including a casing having an opening, a ring secured to said casing around said opening and inclined to a vertical plane, a flange extending inwardly from said ring forming a dust bag seat spaced from the front surface of the ring, and a dust bag having a ring resting on said flange with the mouth of the dust bag opening upwardly, said first-named ring having two tapered cavities at the bottom extending from the front surface to said flange whereby said dust bag ring may be grasped at the bottom and pivoted upwardly against the shoulder at the top of the ring between the front surface and the flange for removing the dust bag from the casing without disturbing the dust collected within the bag.

GUSTAF EINAR LOFGREN.
